K. Frazer

Bridle Bit

No 17268.

Patented May 12, 1857

UNITED STATES PATENT OFFICE.

KASSON FRAZER, OF SYRACUSE, NEW YORK.

METHOD OF CONNECTING THE CHEEK-PIECE TO THE MOUTHPIECE OF BRIDLE-BITS.

Specification of Letters Patent No. 17,268, dated May 12, 1857.

To all whom it may concern:

Be it known that I, KASSON FRAZER, of the city of Syracuse, in the county of Onondaga and State of New York, have invented a new and useful Improvement in Bridle-Bits; and I do hereby declare the following to be a full, clear, and exact description of the construction thereof, reference being had to the annexed drawings, making part of this specification.

My invention consists in the method hereinafter described of connecting the cheek-piece of bridle bits to the mouth-piece.

To construct my invention, cast the mouth piece (A) in the usual form, and having a chamber (E) cast within the bulb at each end. At each side of the chamber (E) make a circular opening for receiving the shank (C) of the cheek-piece (B) and pass a rimmer through the openings in order to make them true and of the same diameter. Cast the cheek piece (B) with necks or grooves (D) upon that portion which is placed within the bulb of the mouth piece, and cut the shank apart in the center. Pass each part of the shank (C) into a cutting tool making them of the same diameter as the openings into the chamber of the bulb. Draw the shanks apart sufficiently to place them into the bulb, and cast in melted zinc or other substance. Through an opening (F) in side

of the bulb so that the same shall flow around and fill the necks on the shanks of the cheek piece, and also the chamber within the bulb.

It is obvious that as the melted metal becomes hardened by cooling, the shanks will be firmly held together, and within the bulb of the mouth piece. Heretofore the cheek pieces of bits have been placed within the mold and the mouth piece cast so as to embrace the shanks within the bulb, in which case they are found to turn with difficulty, and are often broken in the effort at turning the one within the other. By this method of connecting them, they are found to work easily without cramping, and may be plated separately before being connected which is a great advantage.

What I claim as of my own invention and desire to secure by Letters Patent, is—

Constructing cheek pieces of bridle bits by making a neck at each extremity within the ball of the mouth-piece, and securing the same therein by means of filling the chamber around the necks with metal or other composition substantially in the manner and for the purpose set forth.

KASSON FRAZER.
